UNITED STATES PATENT OFFICE.

MAX BRENNEISEN, OF BERNE, SWITZERLAND.

DUST-SUCKING APPARATUS FOR AUTOMOBILES.

1,406,530.

Specification of Letters Patent. Patented Feb. 14, 1922.

Application filed August 31, 1921. Serial No. 497,446.

To all whom it may concern:

Be it known that I, MAX BRENNEISEN, a citizen of the Republic of Switzerland, and resident of Berne, in the Canton of Berne, Switzerland, have invented certain new and useful Improvements in Dust-Sucking Apparatus for Automobiles, of which the following is a specification.

The present invention relates to dust-sucking apparatus for automobiles and more particularly for heavy motor-lorries, and its characteristic features are, firstly, the provision at the underside of the chassis of at least one dust-collecting receptacle having a series of vertically disposed and movable sieves or sifting plates mounted therein, one sieve behind the other and each of finer quality than the preceding one; secondly, at least one suction pipe connected to and made to communicate with the receiving end of the receptacle and having a mouth-piece which is hinged to the free end of said pipe and adapted to be adjusted from a horizontal position to a position in which it follows the curvature of the lorry-wheel to a point near the ground; thirdly, a ventilator mounted at the rear end of the row of sieves and adapted to discharge the dust-free air into the atmosphere; fourthly, gearing to actuate the ventilators, which gearing is coupled to and made dependent from the motor-shaft; and lastly, means to enable the driver of the lorry to shake the sieves, to discharge the contents of the dust-collecting receptacles, and to stop the ventilators.

In order that this invention may be clearly understood reference is made to the accompanying drawings, in which:

Fig. 1 represents a cross-section, partly in elevation, of a lorry with the dust-sucking apparatus applied, certain parts of the motor lorry being omitted;

Fig. 2 shows a side elevation of the same, partly in section, and

Fig. 3 shows a plan view, also partly in section.

In these drawings 1 designates the motor of the lorry, 2 the motor-shaft and 3 the casing protecting the shaft 2. At each side 50 of the latter and mounted between the same and the wheel-axles 4 and at the underside of the frame 5 of the chassis is a dust-collecting receptacle 6 the side walls thereof serving as bearings for a common shaft 7 for

the two ventilators hereinafter described. 55 The rotation of this shaft and the ventilators is effected by means of worm-wheels 8 mounted on said shaft 7 and the motor-shaft 2 respectively. At each of the ends and within the receptacles are suspended, in the manner of pendulums, five sieves or sifting-plates 9 of which that nearest the end of the receptacle 6 is comparatively coarse, each of the succeeding sifting-plates being of finer quality than the preceding one. A 65 rod 10 extending longitudinally through and bearing in the lower portions of the end walls of the receptacle is provided with a number of flanges 11, one such flange being situated at either side of each of the sifting- 70 plates 9 so that when the said rod is moved to and fro, the flanges are caused to knock against the suspended sifting-plates, thus shaking off the dust therefrom. The two rods 10, at the ends extending to below the 75 driver's seat, carry each a handle bar 35 which is within easy reach of the driver, the latter in this way being enabled to actuate the sieve-shaking device as and when desired. 80

The ends of the receptacles 6 are furthermore connected to and made to communicate with suction-pipes 12 of which the mouth-piece 13 is so constructed that it is adapted to fit close to the corresponding lorry-wheel, 85 the end of the mouth-piece reaching hereby to a point near the ground. Each mouth-piece is moreover made to form part of a sleeve 14 rotatably mounted at the end of the pipe 12 so that the mouth-pieces may be lifted 90 into the position shown in dotted lines in Fig. 2. For such purpose I provide each of the sleeves 14 with a projection 15 to which is linked a rod 16, this rod in turn being connected with the slotted end 19 of a lever-arm 18 fixed upon a shaft 17 which is mounted transversely of the driver's platform. A lever 20 secured to the shaft 17 in a central position thereof makes it possible for the driver simultaneously to move all the rods 100 16 and consequently adjust all the mouth-pieces of the pipes 12 at the same time. The lever 20 is double-armed its downwardly extending arm 21, by means of a controlling rod 36, being connected with one part 22 of 105 a coupling on the motor-shaft 2. This part 22 is adapted to be adjusted on said motor-shaft by a nut and spring (not illustrated),

and the other part of the coupling is formed by a sleeve 23 loosely fitting on the motor-shaft and carrying one of the aforesaid worm-wheels 8. The disposition of these parts is hereby such that when the adjustment by the lever 20 of the mouth-pieces into the position shown is effected, a coupling of the shaft 2 with the corresponding worm-wheel is simultaneously taking place.

10 The bottom of the receptacles 6 fitting close to the lower edge of the sifting-plates 9 is formed of three traps or holding flaps 24 designed to shut the receptacle tightly and hinged to the ends thereof, as at 25, in 15 such a manner, that they are adapted to be opened and closed together, Fig. 1. One of the rods 25 serving as hinges for the traps 24, by means of a wire or rope 27, is connected with a draw-bar having a handle 28, 20 the rope 27 being guided by rollers 26 and the said draw-bar being mounted in and guided by a support 29 arranged close to the seat of the driver. This draw-bar may be adjusted and secured in two positions, 25 namely, in a lower position corresponding with the open position of the traps 24 and in a top position in which the traps are closed.

Each dust-collecting receptacle 6 possesses 30 a ventilator 30 with a suitable housing therefor. Both these ventilators are mounted on the common shaft 7 and so fitted to the inner side walls of the receptacles that the dust-charged air, when the mouth-pieces 13 are 35 in the position shown, is caused to be sucked from both ends of the receptacles through the pipes 12 against the sifting-plates 9 where the air is freed from the dust and caused to be discharged at the periphery of 40 the ventilator vanes into the atmosphere.

Between the series of sifting-plates arranged at either end of the receptacles there is a chamber 31 into which projects a sieve 32 of truncated shape forming part of or 45 being attached to the inner wall of the receptacle. This sieve thus prevents the penetration from the receptacle into the ventilator housing of any refuse and in order always to keep the sieves 32 clean, a tapered 50 brush 33 is fixed on the ventilator shaft 7 which brush, during the action of the ventilators, continuously frees the sieves 32 from dust. The truncated body of the brush is hereby provided with openings through 55 which the pure air may enter unhindered.

And in order to prevent the penetration of larger pieces of refuse such as leaves or paper into the mouth-pieces 13 the latter are fitted at their faces with a wire or the like 60 netting, while dust-sweeping brushes 34 are secured to the chassis of the lorry in such a way that the said nettings, when the mouth-pieces are raised into the position indicated in dotted lines, Fig. 2, are cleaned by the 65 brushes 34.

Having thus fully described my said invention what I claim and desire to secure by Letters Patent is:—

1. In the herein-described dust-sucking apparatus for automobiles, the combination, 70 of at least one dust-collecting receptacle mounted at the underside of the chassis of the automobile, a series of sifting-plates arranged within and at each end of the receptacle and pivotally suspended from the top thereof, a suction-pipe connected to and communicating with each end of the receptacle, a mouth-piece hinged to the free end of each of the suction-pipes and arranged close to the wheel of the automobile, a ventilator and 75 housing therefor mounted at the rear of the series of sifting-plates and communicating with the receptacle, means to actuate and stop the ventilators, means to shake the sifting-plates, and means to discharge the contents from the aforesaid receptacle. 80

2. In the herein-described dust-sucking apparatus for automobiles, the combination, 85 of a dust-collecting receptacle mounted at the underside of the chassis of the automobile and at either side of the motor-shaft and between the same and the automobile-wheels, a series of sifting plates arranged within and at each end of each of the receptacles and pivotally suspended from the top thereof, a suction-pipe connected to and communicating with each end of the said receptacles, a mouth-piece hingedly connected with the free end of the suction-pipe and arranged close to the wheel of the automobile, means to adjust the mouth-piece in a vertical direction, a ventilator and housing 90 therefor mounted between the two series of sifting plates of each receptacle and at the inner side of same, means to actuate the ventilators, means to shake the sifting plates, and means to discharge the contents from the receptacles. 95

3. In a dust-sucking apparatus for automobiles, the combination, of a dust-collecting 100 receptacle mounted at the underside of the chassis of the automobile and at either side and between the motor-shaft and the automobile-wheels, a series of sifting plates arranged within and at each end of each of the receptacles and pivotally suspended from the top thereof, the said sifting plates being one behind the other and increasing in fine- 105

ness towards the central part of the receptacle, a suction-pipe connecting with each end of each of the receptacles and communicating therewith, a mouth-piece hinged to the free end of each of the suction-pipes and fitted close to the auto-wheels, means to adjust the mouth-pieces in a vertical plane, a ventilator and housing therefor mounted between each two series of sifting plates and at the inner side of the receptacles, a sieve of truncated form attached to the said inner side of the receptacle and projecting between 110 115 120 125 130

the opposite sets of sifting plates, means to clean the sieves when the ventilators are actuated, means to actuate and stop the said ventilators, means to shake the sifting plates, and means to discharge the contents of the receptacles, all substantially as and for the purpose set forth.

In testimony whereof I have hereunto set my hand in the presence of two subscribing witnesses.

MAX BRENNISEN.
